UNITED STATES PATENT OFFICE.

SAMUEL J. SIEGEL, OF NEW YORK, N. Y., ASSIGNOR TO J. B. CAMPBELL MANUFACTURING CO., OF SALEM, NEW JERSEY, A CORPORATION OF NEW JERSEY.

DESIGN FOR OILCLOTH OR SIMILAR ARTICLE.

Application filed April 26, 1924. Serial No. 9,412. Term of patent 3½ years.

To all whom it may concern:

Be it known that I, SAMUEL J. SIEGEL, a citizen of the United States, and a resident of 817 West End Avenue, in the city, county, and State of New York, have invented a new, original, and ornamental Design for an Oilcloth or Similar Article, of which the following is a specification, reference being had to the accompanying drawing, forming part of this specification.

The figure is a plan view of a piece of oilcloth embodying my design.

I claim:

The ornamental design for oilcloth or similar article as shown.

In witness whereof, I have hereunto signed my name this 23 day of April, 1924.

SAMUEL J. SIEGEL.
